UNITED STATES PATENT OFFICE.

WILLIAM CORNER PRATT, OF HORNSBY, NEAR SYDNEY, NEW SOUTH WALES,
AUSTRALIA.

AUXILIARY LOCK FOR DOORS AND WINDOWS.

Application filed April 2, 1924. Serial No. 703,777.

To all whom it may concern:

Be it known that I, WILLIAM CORNER PRATT, a subject of the King of Great Britain, residing at Hornsby, near Sydney, in the State of New South Wales, Commonwealth of Australia, have invented new and useful Improvements in Auxiliary Locks for Doors and Windows, of which the following is a specification.

10 This invention consists in a locking device usable on hinged doors and windows, and also on sliding doors and windows, for securing the same in fully closed or partially open position in such a way that they 15 may be released for full opening to admit a person only by the action of a person located within the apartment.

The device consists of a slotted metal arm which is detachably held in a fixed staple 20 secured to the door or window jamb or frame and a latch lock fixed on the door or window and adapted to co-act with said arm to limit the extent of opening of the door or sash. The stub end of the slotted 25 arm is offset and is slid into a staple which is a permanent fixture on the post or frame. The bolt of the latch is slotted so that when partially retired the slots come to register with the edges of the slot in the bracket 30 arm, permitting the door or sash to be opened only so far as the slot extends, that is, sufficient only for the purpose of facilitating ventilation. The part of the slot near the bent stub end of the bracket arm 35 is notched to offer sufficient width to enable the latch bolt to be shot and retired. When the bolt is extended or "shot" so that the slot in it comes beyond the edge of the bracket arm slot it acts as a lock to prevent 40 opening of the door. As the latch bolt can be retired only when the door or sash is fully closed, access cannot be had to the apartment from outside. A keeper is fitted on the bracket arm near the stub end of it 45 to engage one of the slots in the bolt and prevent withdrawal of the bolt even whilst the door or window is in fully closed position. This keeper must be released by a person within the apartment in order to 50 free the latch bolt, but it is reset automatically when the latch bolt traverses the slot in the closing movement of the door, so that when the door has been closed the keeper is found restored to its original position and the voluntary action of a person

within the apartment is necessary to free the lock. Another keeper is in the shape of a check-pawl arranged at the inner end of the slotted arm to engage the lock bolt and hold the door or window in the partially 60 open position to facilitate ventilation.

In the accompanying drawings—

Figure 1 is a perspective elevational view showing the device fixed on a hinged door with the bolt partially shot and its slots 65 engaged with the slot edges in the bracket arm;

Figure 2 is a fragmentary perspective elevational view showing the attachment arm arranged as a sliding window check; and 70

Figure 3 is a fragmentary perspective view showing the bolt in the fully "shot" position.

In the case of a hinged door or window, the slotted arm 10 is curved to the radius 75 of the door or window sweep; in the case of a sliding door or window in which the arrangement shown in Fig. 2 or an adaptation thereof is used, the slotted bracket 10 is straight. 11 is the slot in the bracket 80 arm 10, and 12 the notched portion of same in register with the spring bolt 13 of the latch when the door or window is in fully closed position. The stub end of the slotted bracket arm 10 is bent to form a tang 14 85 which is slid into the fixed staple 15. This staple is secured to the door frame or post 16 by a screw or screws, the heads of which are covered by the tang 14 when same is inserted. The tang 14 is held in position 90 in the staple 15 by means of a screw 17.

The latch bolt 13 is housed in a casing 18 and the bolt is backed by a spring which normally tends to force it outward. The casing is fixed to the door or sash by a screw through its back plate, a hole 35 being made in the case back to offer access to the head of this screw when the bolt 13 is removed from its housing. The tail of the bolt 13 is formed as a finger piece 19 to facilitate 100 its withdrawal. A keeper freely pivoted at 21 to the housing 18 is provided for engaging the finger piece 19 to hold the bolt 13 in retired position and to prevent it from engaging the slotted bracket. 105

At top and bottom the nose of the bolt 13 is slotted as shown at 22 and 23. These slots align with the edges of the bracket arm slot 11 when the bolt is partially retired, and the door may then be swung open with 110

the bolt 13 engaged in the slot 11. The extent of opening of the door or window is then limited by the length of the slot 11, the fully open position being indicated in dotted lines. At this position the bolt 13 may be chocked by means of the pawl 24 to prevent accidental reclosing of the door. 5 25 is a keeper freely pivoted midway of its length on a pin 26 on the outer side of the bracket arm 10 near the stub end of it. The lower part of this keeper 25 should be chamfered as shown at 25^x. The width of the slot 22 in the top of the bolt head 13 is sufficient to accommodate not only the 10 thickness of the slotted bracket 10 but also the thickness of the keeper 25. The pivot 26 is so positioned that in the fully closed position of the door or window the forward end of the keeper may set in the bolt slot 22. The keeper must be tilted upwardly to free its forward end from the bolt slot 22 before the bolt 13 can be withdrawn to allow of the door or window to be opened to a greater extent than is permitted by 15 the range of the slot 11. In the opening movement, so long as the bolt 13 is in the position shown in Fig. 1, the keeper 24 is reset automatically and it does not become released unless manipulated when the door 20 or window is brought to the shut position. 25 On the keeper 20 being released the bolt 13 is shot by its spring. When the door or window is normally shut and the keeper 25 is tipped up (see Fig. 3), the bolt 13 will be fully shot through the notched portion 12 of the slot 11 and will lock the door or window in the fully closed position. If the bolt be withdrawn till its slots 22 and 23 register with the edges of the slot 11, the door 30 or window may be swung open as far as the length of the slot 11 permits, and until the door or window has been again brought to the fully closed position and the keeper 25 tilted to the free position and the bolt 13 withdrawn by the occupant of the apartment, it will not be possible for a person 35 to enter the apartment from without. Even if the door or window be left open to the full extent permitted by the length of the slot 11, it would be useless for an intruder to insert his arm through the open portion and set the keeper 25, for in the closing movement to bring the bolt 13 to the clearance notch 12 at the base of the slot 11, the 40 keeper will be automatically reset at the locked position or will chock the bolt so that it cannot enter the slot notch and the bolt cannot in either of these conditions be withdrawn. Perfect security for the occupant of the apartment is therefore assured. 45 When the bolt is set back by means of the keeper, the device is inoperative and the door or sash may then be closed and fully opened in the usual way. If the bolt be held back manually the door or sash will be

freed to open fully. Then if closed after the bolt has been released by the hand the bolt will become automatically re-engaged in the slot as soon as full closed position is reached.

70

In the case of the window latch type of fastener shown in Fig. 2, another form of keeper is substituted for the swing keeper 20 shown in Fig. 1. The keeper in this case may be a clip 30, the nose 31 of which takes over the end of the bolt 13 whilst its rear part is engaged by the the upset tang 32 projecting upward from the back of the bolt housing 18. The back plate 28 which carries the lock case 18 is slotted to offer 75 clearance for the slotted bracket 10. The bracket 10 is thus held always to register in relation to the lock bolt so that the functioning of the device is not interfered with if the bracket 10 should be accidentally bent out 80 of its true position.

85

The device is usable alone to function as the normal locking means, and also as means for permitting a limited movement only of a door or window, or it may be used as a 90 supplemental locking device operative with or independently of other latching or locking devices.

95

What I do claim is:

1. A locking device for limiting the degree of opening of doors and windows and for fastening the same in closed position, comprising a bracket arm with closed end longitudinal slot therein, a latch bolt deeper than the width of the slot, and having slots 100 across the top and bottom faces of its head which slots register with the edges of the slot in the bracket arm when the bolt is partially shot, a clearance space for the bolt head at the base of the bracket arm slot, and a keeper engageable in one of the bolt nose slots and pivotally mounted on one side of the bracket arm, with one end of it disposed across said clearance space to partly close 105 said space.

110

2. A locking device for limiting the degree of opening of doors and windows, consisting of a spring latch bolt with cross slotted head co-acting with a closed end slot in a bracket arm by sliding engagement 115 of the cross slots with the edges of the bracket arm slot, a clearance space at one end of said bracket arm slot to permit bolt movement therethrough to engage and disengage the bolt and the bracket arm, and a pivoted keeper on the bracket arm engageable with one of the bolt cross slots and disengageable therefrom only whilst the bolt is in register with the clearance space.

120

3. A locking device for limiting the degree of opening of doors and windows, consisting of a slotted bracket arm 10 with staple mounting tang 14, a clearance way 12 at the base of the slot 11 in alignment with the bolt head 13 in the closed position of 125 130

the door or window, a spring latch bolt 13 having its head cross notched at 22-23 to register with the edges of the slot 11, a keeper 25 pivotally mounted at 26 rearward 5 of the lock bolt, and with its inner end projecting across the clearance space 12, means for manipulating the bolt 13 and for checking it in retired position and a check pawl 24 adapted for chocking the bolt in the fully 10 open position of the door or window, said keeper 25 adapted to reset automatically in the closing movement of the door or window to hold the bolt engaged by it at the clearance space until said keeper 25 is manipulated from within the apartment to clear the 15 bolt and permit its retirement, substantially as described.

In testimony whereof I affix my signature in the presence of two witnesses.

WILLIAM CORNER PRATT.
